TYPEWRITING AND LIKE MACHINE

Russell G. Thompson, Elmira, N. Y., assignor to
Remington Rand Inc., Buffalo, N. Y., a corporation of Delaware

Application July 26, 1940, Serial No. 347,677

8 Claims. (Cl. 197—186)

This invention relates to typewriting machines, and more particularly to improvements in the frame structure of such machines.

The main object of this invention is to provide an improved frame structure for typewriting machines wherein a main frame is provided with readily removable cover members, and the major elements of the machine are carried as a unit by an inner frame which is readily removable from the main frame.

It is further proposed to provide an improved means for accurately locating and holding the inner frame within the outer frame and to avoid the necessity of adjusting the position of the inner frame each time it is placed in the main frame.

It is also proposed to provide means for operatively connecting various devices on the inner frame with associated parts on the main frame in a manner to permit the inner frame to be removed from the main frame without individually manipulating any of the connecting parts.

Other objects, purposes and characteristic features of this invention will appear as the description thereof progresses, during which references will be made to the accompanying drawings, in which:

Fig. 1 is a vertical, side sectional view of a typewriting machine arranged in accordance with the present invention, the view showing certain parts broken away and other parts omitted.

Fig. 2 is a fragmentary, front sectional view taken on line 2—2 of Fig. 1.

Fig. 3 is a fragmentary, top sectional view taken on line 3—3 of Fig. 1.

Fig. 4 is a fragmentary, top sectional view of the rear portion of the machine shown in Fig. 1.

Fig. 5 is a fragmentary, perspective view of the rear portion of the inner frame and parts carried thereby.

Fig. 6 is a fragmentary, perspective view of a portion of the inside of the main frame.

Fig. 7 is an enlarged, horizontal, sectional view showing the locating means between the inner frame and the main frame.

Fig. 8 is a vertical, sectional view taken on line 8—8 of Fig. 7.

Fig. 9 is a fragmentary, elevational view of a portion of the mechanism shown in Fig. 7.

Fig. 10 is a fragmentary, sectional view taken on line 10—10 of Fig. 9.

Fig. 11 is a fragmentary, sectional view similar to Fig. 1, but showing the inner frame and parts carried thereby moved slightly out of normal position.

In the illustrated embodiment of the present invention, a main frame structure forms the outer casing for the sides of the typewriting machine and is employed to directly support certain operating parts of the typewriting machine as will later appear. Referring to Figs. 2, 3 and 4, it may be seen that this main frame comprises a right hand side portion 15 and a left hand side portion 16, which portions are joined at their front ends by a low front portion 17 shown in Fig. 11. The rear portions of the sides 15 and 16 of the main frame are rigidly braced by an interconnecting cross member 20 which is connected at its end portions to inwardly extending lugs on the side members 15 and 16 by screws 21 as shown in Fig. 1. The side portions 15 and 16 are further braced by an intermediate channel member 22 secured by means not shown to the lower edges of the side portions.

The side portions 15 and 16 of the main frame are preferably of cast metal having a smooth exterior surface with various bosses and lugs formed integrally on the inner surfaces thereof for mounting certain parts of the machine as shown for example in Fig. 6. It may be seen in Figs. 1 and 4 that the rear cross member 20 is mounted slightly forward of the rearward ends of the side members 15 and 16, and this cross member 20 together with the front portion 17 and channel member 22 rigidly joins the two side members 15 and 16 to provide a rigid main frame structure, having a smooth and very pleasing exterior appearance. This main frame structure is adapted to be supported on a desk top or other supporting surface by four feet 23 which may be of the usual resilient construction mounted on respective inwardly extending portions 24 formed integrally with the side members 15 and 16.

A carriage unit is removably mounted on the rear upper portion of the main frame in the present machine. This carriage unit has not been shown in detail in the present drawings, but may be generally described as including a substantially L-shaped stationary guide rail structure 25 as shown in Fig. 1. This guide rail 25 extends transversely of the machine and is removably mounted upon the top edges of the side members 15 and 16. A locating screw 26 extends upwardly from each of the side members 15 and 16 as shown in Figs. 4 and 6, and these locating screws 26 are received in companion openings in the end portions of the guide rail 25 to thereby hold the carriage unit against lateral shifting in any direction relative to the main frame. In

order to normally hold the carriage guide rail 25 upon the main frame, releasable latch means are provided which may be generally described as comprising a latch member 27 pivotally mounted on each end portion of the guide rail 25 such as the member 27 shown in Figs. 1 and 2. Each of the latch members 27 is spring-pressed to a position wherein a notch at the inner end thereof enters an annular groove in the extending portion of the companion locating screws 26 as shown for example in Fig. 1. Thus, in order to remove the carriage unit, it is merely necessary to manually press the two latch members 27 which moves the inner ends thereof out of the grooves in the locating screws 26 and thereby permits the carriage guide rail structure 25 to be lifted upwardly and off the main frame.

A carriage truck or movable frame is mounted for movement transversely of the machine on the guide rail structure 25. This movable carriage frame structure may be generally the same construction as that employed in the usual Remington Model No. 17 machine, and may be briefly described as comprising an inclined rail member 30 having guide-ways at its upper and lower edges. Anti-friction rollers 31 (see Fig. 1) are provided between these guide-ways in the rail 30 and oppositely disposed guide-ways in the stationary rail 25 whereby the carriage is mounted for free longitudinal movement. The carriage rail 30 is provided with the usual carriage end plates (not shown) in which a platen 33 is mounted for turning movement in the usual manner.

The carriage is moved in the letter spacing direction from right to left of the machine by a spring drum 35 as shown in Fig. 4, which spring drum is mounted on the front side of the cross member 20 of the main frame and is connected by the usual spring drum tape (not shown) to the movable carriage frame. The letter spacing movements of the carriage under the force of the spring drum 35 are controlled by the usual escapement mechanism shown in part in Figs. 2 and 4. This escapement mechanism includes an escapement wheel 37 which is mounted to turn around a screw 38 secured to a bracket 39 (see Fig. 4) mounted on the cross member 20 of the main frame. A pinion gear 40 is connected to the escapement wheel 37, and this pinion meshes with a feed rack 48 which is mounted on the movable carriage frame in the usual manner.

A dog rocker mechanism cooperates with teeth 37' of the escapement wheel 37, which dog rocker mechanism includes a rocker bracket 42 as shown in Fig. 4. The bracket 42 is mounted for rocking movement about trunnions 43 carried by the bracket 39. A normally engaged holding dog 44 is pivotally mounted on the rocker bracket 42, and a spring 45 acts on the bracket 42 to normally hold the end of the holding dog 44 in engagement with a tooth 37' of the escapement wheel as shown in Fig. 4. A stepping dog 46 is formed integrally with the rocker bracket 42 to cooperate with the escapement teeth 37' when the rocker bracket is moved against the force of the spring 45.

From the foregoing description, it will be noted that the carriage and parts, such as the spring drum and escapement mechanism, which are directly associated therewith for controlling its letter spacing movements are all mounted on the main frame of the machine, and in accordance with the present invention, the printing instrumentalities such as the type action and other parts related thereto are mounted on an inner

frame which is removably mounted within the main frame. Referring particularly to Figs. 1, 2, 3, 4 and 5, it may be seen that this inner frame comprises a right-hand side plate 48 and a left-hand side plate 49, both of which are generally similar in shape and construction. The two side plates 48 and 49 are rigidly interconnected by three cross members 50, 51 and 52, each of which is connected at its end portions by screws 53 to the side plates.

Referring to Figs. 1 and 3, it may be seen that the lower rear cross member 50 is provided with spaced slots for receiving the rearward ends of printing key levers 54 which are pivotally mounted on a wire 55 carried by the cross member 50. The key levers 54 extend forwardly from the cross member 50 through slots in a guide comb 57 secured at 58 to each of the side plates 48 and 49. The front ends of the key levers 54 extend upwardly in the usual manner and are provided with finger keys 60.

The lower front cross member 51 is likewise provided with spaced slots which receive sub-levers 62 pivotally mounted on a wire 63 carried by the cross member 51. The intermediate portion of each of the sub-levers 62 is connected by a link 64 to an upstanding portion on the companion key lever 54, and a returning spring 65 acts on each of the sub-levers 62 in the usual manner.

A type bar segment 67 is mounted on the upper cross member 52 for case shifting movement in the manner disclosed in the co-pending application Serial No. 292,461 filed August 29, 1939. The segment 67 carries type bars 68 mounted in radial slots therein to move to and from printing position about a fulcrum wire 69. Each type bar 68 is operated by its companion sub-lever 62 regardless of its case shifted position by a connecting link 70 extending from the lower rearward part of the type bar to the upper end of the companion sub-lever.

Referring to Figs. 1, 2 and 5, it may be seen that a universal member in the form of a semi-circular bar 73 is mounted on the segment member 67 to be actuated by the printing movement of any one of the type bars 68 in the usual manner. This universal bar 73 is provided with rearward extensions which are pivotally connected to upstanding portions of a rock shaft 74 which is pivotally mounted on a bracket 75 secured at 76 to the segment member 67. The front portion of the universal bar 73 is supported for movement by the type bars by an upwardly extending portion 77 which carries a pin 78 adapted to slide in an opening in the segment member 67.

The inner removable frame thus carries the key levers and type actions of the present machine as well as other associated mechanism which will later be described. In accordance with the present invention, this inner frame is mounted within the main frame for ready removal therefrom and in a manner which securely and accurately positions the type actions and associated parts in proper relation to the carriage and other parts on the main frame co-operating therewith.

Referring to Figs. 1, 2 and 6, it may be seen that an inwardly extending shelf portion 85 is formed integrally with the lower edge portion of each of the side members 15 and 16 of the main frame. When the inner frame structure is placed within the main frame, these shelf portions 85 on the main frame are adapted to support the weight of the inner removable frame

structure by engaging the lower edges of the side plates 48 and 49. In order to prevent lateral displacement of the inner frame with relation to the main frame, a guide strip 86 is secured by screws 87 on the upper surface of each of the shelf portions 85. These guide strips 86 are located so that the inner edges thereof engage the lower outside edges of the side plates 48 and 49 of the inner frame as shown particularly in Fig. 8.

In a typewriting machine, it is necessary to very accurately locate the type bar segment with relation to the platen or the carriage in a fore-and-aft direction. If the type bar segment is located a slight distance too far in front of the platen, or a slight distance too far in the rear of the platen, or if there is a possibility of relative shifting movement between the type segment and the platen, improper printing will obviously result. Accordingly, means have been provided in accordance with the present invention for very accurately locating the inner removable frame with relation to the main frame and to securely hold these parts in such relative position in order to insure that the type bar segment is always properly positioned with relation to the platen.

Referring to Figs. 1, 2 and 4, a locating means in the form of a horizontally disposed bar 90 is adjustably mounted on the lower outside surface of each of the side plates 48 and 49 of the inner frame. The particular means for adjustably mounting each of these locating bars 90 on the side plates is shown in Figs. 7 and 8, wherein it may be seen that each of the bars 90 is securely clamped against the associated side plate by screws 91 which pass through elongated openings in the side plate and are threaded into tapped openings in the bar. These openings in the side plates 48 and 49 which receive the screws 91 are elongated in a horizontal direction to permit adjustment of the bars 90 horizontally with respect to the side plates 48 and 49 when the screws 91 are loosened.

In order to facilitate accurate adjustment of each of the bars 90 with relation to the associated side plate, an eccentric adjusting means has been provided in the form of a screw 92 threaded into a tapped opening in each of the side plates 48 and 49 and having an eccentric portion 93 entering a vertically elongated opening in the locating bar 90. Thus when the holding screws 91 are loosened, each of the bars 90 may be very accurately adjusted longitudinally with relation to the associated side plate by turning the screw 92 which will act through the eccentric portion 93 to move the bar either forwardly or rearwardly to the desired position. The holding screws 91 may then be tightened to securely lock the locating bars 90 in their adjusted position.

The front and rear ends of the locating bars 90 coact with means on the main frame for preventing displacement of the inner frame either forwardly or rearwardly from normal position. Thus, as may be seen in Figs. 1, 2 and 7, a headed screw 95 is threaded into an inwardly extending boss portion on each of the side members 15 and 16 of the main frame. When the inner frame assembly is placed within the main frame, the front ends of the locating bars 90 engage the heads of the screws 95 which constitute an abutment preventing any forward dis-

placement of the inner frame with relation to the main frame.

Inasmuch as the inner frame assembly must be very securely held within the main frame against forward or rearward shifting movement, means are provided in accordance with the present invention which coact with the rearward ends of the locating bars 90, which means are made adjustable with relation to the front 10 abutments 95 so that the space therebetween may be closely adjusted to accord with the length of the locating bars 90. This adjustable abutment is formed as shown in Figs. 9 and 10 by a curved arm 98 pivotally mounted at its upper end at 99 on an inwardly extending boss on each of the side members 15 and 16 of the main frame. The lower end of each of the curved arms 98 is provided with a vertically elongated opening receiving an adjusting member 100 having an eccentric opening therein receiving the body portion of the holding screw 101 which is threaded into an inwardly extending boss on the associated side member of the main frame.

An inclined portion 98' is provided on the front edge of each of the curved arms 98, and each of the curved arms 98 is adjusted through the eccentric member 100 so that this inclined portion 98' snugly engages the curved rearward end of the associated locating bar 90 when the front end of this bar is in engagement with the head of the associated screw 95. The inclined portions 98' on the adjustable arms 98 thus operate on the rearward ends of the locating bars 90 to prevent rearward displacement of the inner frame assembly with relation to the main frame, and also to prevent any upward displacement of the rear portion of the inner frame.

Releasable latching means are provided in accordance with the present invention for normally holding the front end of the inner frame assembly against upward displacement with relation to the main frame. Referring to Figs. 1, 2 and 3, this releasable latching means comprises a pivoted latch arm 110 mounted on the outer side of each of the side plates 48 and 49 of the inner frame. Each of these latch arms 110 is pivotally mounted by a shoulder screw 111 threaded into the associated side plate, and the upper portion of each of the latch arms 110 is provided with a notch 112 which coacts with the head of an associated screw 113 threaded into a boss extending inwardly from each of the side portions 15 and 16 of the main frame.

The lower edge portion of the notch 112 in each of the latch arms 110 is inclined as shown particularly in Fig. 1 so that a wedging or camming action is effected thereby on the head of the associated screw 113 as the latch arm 110 is drawn rearwardly under the force of an associated contractile spring 115. Each of the springs 115 extends between the upper end of the associated arm 110 and a pin 116 on the associated side plate. When the inner frame assembly is in position within the main frame, the arms 110 are thus operated by the springs 115 to a position wherein the camming surfaces at the lower portion of the notches 112 coact with the heads of the screws 113 to securely hold the front portion of the side plates 48 and 49 in engagement with the shelf portions 85 of the main frame.

When the inner frame is placed within the main frame the weight is supported by the shelf portions 85 of the main frame while lateral displacement is prevented by the guide strips 86

and forward or rearward displacement is prevented by the cooperation of the abutments 95 and 98 with the ends of the locating bars 90. Upward displacement of the rearward end of the inner frame is prevented by the action of the abutment arm 93 on the rearward ends of the locating bars 90, while upward displacement of the front end of the inner frame is prevented by the action of the spring-pressed latch arms 110 on the screws 113. Each of the arms 93 may be individually adjusted in the manner previously pointed out to effect a snug engagement of the ends of each of the locating bars 90 with the co-operating abutments 95 and 98'. The inner frame may also be adjusted with relation to the locating bars 90 by releasing the holding screws 91 and turning the eccentric adjustments 92 until the exact forward and rearward position and the correct relative alignment of the inner frame is obtained with relation to the platen 33 and other cooperating parts carried by the main frame. The holding screws 91 and 101 may then be securely tightened so that the inner frame is rigidly retained in its proper position.

The entire inner frame assembly may be easily and quickly removed from the main frame by merely operating both of the latch arms 110 forwardly and then raising the front portion of the inner frame upward so that the front ends of the locating bars 90 are above the heads of the screws 95. The inner frame may then be easily removed from the machine by an upward and forward movement as shown in Fig. 11. In replacing the inner frame assembly, it is moved downwardly and rearwardly toward the position shown in Fig. 11, after which a rearward movement will cause the rearward ends of the locating bars 90 to engage the inclined surfaces 98' of the arms 93 and the front ends of the locating bars will then move into position behind the heads of the screws 95. The inclined surfaces 98' exert a camming action on the rearward ends of the locating bars 90 thereby insuring that the rearward portion of the inner frame is in proper position upon the shelf portions 85 of the main frame. Thus, when the forward ends of locating bars 90 move into position behind the heads of the screws 95, the latch arms 110 cooperate with the screws 113 of the main frame under the force of the springs 115 to insure that the front portion of the inner frame is securely held in proper position upon the shelf portions 85.

The escapement dog rocker 42 which is mounted on the main frame is operated by the universal bar 73 which is mounted on the inner removable frame, and accordingly means are provided in accordance with the present invention for operatively connecting the universal bar 73 with the dog rocker 42 without in any manner interfering with the removal and replacement of the inner frame assembly with relation to the main frame. Referring to Figs. 1, 2, 4 and 5, the rearward extension at the left-hand side of the universal bar 73 is provided with a contact portion 128 which cooperates with a pin 121 at the end of an upstanding arm 122 (see Fig. 1) on a rocker bracket 123. This rocker bracket is pivotally mounted at 124 on a U-shaped bracket 125 which depends from the horizontal portion at the top of the rear cross member 29 of the main frame. A depending arm 127 (see Fig. 2) on the rocker bracket 123 is pivotally connected by a link 128 to the dog rocker 42 whereby the rearward operating movement of the universal bar 73 operates through the abutting parts 120 and 121 to cause

operation of the dog rocker 42. These separable connecting parts 120 and 121 obviously permit the inner frame to be readily removed from the main frame and readily replaced therein without manipulation of any of the parts connecting the universal bar with the escapement dog rocker.

The present machine also includes a key operated back-spacing mechanism cooperating with the escapement wheel 37 to cause a back-spacing movement of the carriage. Referring to Figs. 1 and 3, a back-space key lever 132 is pivotally mounted on the cross member 50 of the inner frame, and a rearwardly extending arm 133 on this back space lever is provided with a pin 134 which cooperates with a rearwardly extending arm 135 of a rocker bracket 136. This rocker bracket is pivotally mounted at 137 on a bracket 138 secured to the rear cross member 20 of the main frame as shown in Fig. 4. The lower end 20 of a back spacing pawl 140 is pivotally connected in the usual manner to a rearwardly extending arm 141 on the rocker bracket 136.

An operation of the back-space key lever 132 operates through the abutting connections 134 and 135 to cause an upward movement of the back spacing pawl 140 which cooperates with the escapement wheel 37 to cause a back-spacing movement of the carriage in the usual manner. These separable connecting parts 134 and 135 however permit the inner frame assembly to be readily removed and replaced with relation to the main frame without manipulating the operative connection between the back space key lever on the inner frame and the back spacing mechanism mounted on the main frame.

The space bar mechanism in the present machine is entirely mounted in the main frame, and comprises a space bar 145 (see Fig. 11) mounted at the front end of parallel levers 146 which are secured at their rearward ends to a square rock shaft 147 as shown in Fig. 3. The rock shaft 147 is mounted on pivot screws 148 (see Fig. 2) extending endwardly from the two side portions 15 and 16 of the main frame, and an arm 149 extends rearwardly from the rock shaft 147 for operating the dog rocker bracket through a connecting link 150 in the usual manner.

A tabulator mechanism is also provided in the present machine which includes a tabulator bar 155 mounted at the end of parallel arms 156 which are pivotally mounted on a cross bar 157 extending between the side plates 48 and 49 of the inner frame as shown in Figs. 1 and 3. A depending portion of one of the tabulator arms 156 is pivotally connected by a link 162 to the depending arm of a bell crank 158 (see Fig. 5) which is mounted in a guide slot in the cross member 52 of the inner frame to turn about a pivot rod 159. The rearward extending end of the bell crank 158 is provided with an adjustable contact screw 163 as shown in Fig. 5, which contact screw is normally in a position to coact with the lower end of a tabulator stop in the form of a vertically disposed slide 160 shown in Fig. 2. This stop slide 160 is mounted in the main frame of the machine by a slotted guide bar 161 (see Fig. 2) secured to the rear cross member 29 of the main frame and by a slot in the lower horizontal portion of the U-shaped bracket 125. The upper end of the stop member 160 is operated upwardly by depression of the tabulator bar 155 into a position cooperating with tabulator stops (not shown) mounted on the carriage.

The tabulator mechanism also includes a tabulator stop-set key 165 (see Fig. 3) which is mount-

ed at the front end of an arm 166 of a rocker bracket 167 which is mounted to turn about the cross bar 157. A depending arm on the rocker bracket 167 is connected by a link 168 to the depending arm of a bell crank 169 which is similar to the bell crank 158 and is mounted in a slot in the cross member 52 of the inner frame to turn about the pivot rod 159. The rearwardly extending portion of the bell crank 169 is provided with an adjustable contact screw 170 (see Fig. 5) which normally cooperates with the lower end of a slide member 171 (see Fig. 2). This slide member is guided by the slotted bar 161 and a slot in the bracket 125 on the main frame in a similar manner to the stop member 160. The upper end of the slide member 171 cooperates with mechanism (not shown) on the carriage to project the carriage tabulator stops into effective position in the usual manner.

The tabulator mechanism further includes means for clearing or restoring the carriage stops to ineffective position which comprises a stop clear key 173 at the front end of an arm 174 of a rocker bracket 175 which is mounted to turn about the cross bar 157. A depending portion on the rocker bracket 175 is connected by a link 176 to the depending portion of a bell crank 177 which is similar to the bell cranks 158 and 169 and is likewise mounted in a slot in the cross member 52 of the inner frame to turn about the pivot rod 159. The bell crank 177 is likewise provided with an adjustable contact screw 178 which cooperates with the lower end of a slide member 179 which is likewise mounted on the main frame by the slotted guide bar 161 and a slot in the bracket 125. The upper end of the slide member 179 is shaped to coat with the carriage tabulator stops when operated upwardly by a depression of the clear key 173 in a manner to cause these carriage stops to be cammed back to ineffective position by the movement of the carriage.

The tabulator mechanism of the present machine thus includes key lever mechanism mounted on the inner removable frame as well as parts operated thereby which are mounted on the main frame, and the operative connections provided by abutting relation of the contact screws 163, 170 and 178 with the lower ends of the slide members 160, 171 and 179 respectively provide separable connections permitting the inner frame to be readily removed from the main frame without individual manipulation of any of these operative connections.

The present machine also includes mechanism for releasing the carriage margin stops comprising a margin release key 185 at the front end of a key lever 186 which is mounted to turn about the pivot wire 55 carried by the cross member 50 of the inner frame. An arm 187 (see Figs. 1 and 5) extends rearwardly and upwardly from the key lever 186 and the end thereof is provided with a contact portion 188 which coats with a pin 189 at the lower end of a bell crank 190 carried by a bracket 191 secured to the cross member 20 of the main frame, as shown in Fig. 2.

The rearwardly extending end of the bell crank 190 coats with the arm of a transverse bell crank 192 (see Fig. 4) which is pivotally mounted at 193 on a boss projecting rearwardly from the rear cross member 20 of the main frame. The upper arm of the bell crank 192 cooperates with a toe portion of a slide member 193 (see Fig. 1) mounted on the detachable guide rail 25 of the carriage structure. The upper end of the slide member 193 is connected to the usual margin

stop bar (not shown) which is mounted on the detachable carriage rail 25 for operating the margin stops to a released position in the usual manner. In this margin stop release arrangement, the key lever mechanism mounted on the inner frame includes a contact portion 188 which is readily separable from the cooperating part 189 mounted on the main frame to permit the inner frame to be readily removed from the main frame without manipulating these interconnecting parts.

Line locking mechanism is also provided in the present machine which functions to prevent effective operation of the printing key levers and the space bar when the carriage reaches a predetermined left hand position. Referring to Figs. 1, 2 and 4, a universal line lock bail 198 is mounted for rocking movement on pivot screws 199 carried by the side plates 48 and 49 of the inner frame. An upstanding arm portion 200 on the bail 198 is operatively connected by a rod 201 to a crank arm 202 (see Fig. 4) which is pivotally mounted at 203 on a bracket 204 secured to the side plate 48. A contractile spring 205 extends between a stop pin on the crank arm and the bracket 204 and normally acts to hold the rod 201 in a rearward position to hold the universal bail 198 in its position shown in Fig. 1.

As shown in Fig. 1, the lower edge of the bail 198 is provided with a rearwardly turned portion 198', which is adapted when the bail is swung rearwardly to pass beneath hooked portions 208 on the upward extensions of the key levers 54. The portion 198' of the bail is also adapted to pass beneath hooked portions on upstanding arms 209 on the space bar levers 146 and thereby prevent an effective operation of the space bar as well as the printing key levers. The spring 205, however, is normally effective thru the connecting rod 201 to hold the bottom of the lock bail 198 in its illustrated forward position wherein the hooked portion 198' does not coat with the portions 208 and 209 of the key levers and thus permits free operation thereof.

The portion of the line lock mechanism thus far described is entirely mounted in the inner removable frame, and this portion of the mechanism cooperates with parts mounted in the main frame which are controlled in the usual manner by the line lock stop mechanism on the carriage. The rearward end of the crank arm 202 is provided with an upturned contact portion 212 adapted to cooperate with the end of an adjustable contact screw 213 carried by the lower end of a swinging arm 214 mounted by a link 215 depending from a bracket 216 secured to the cross member 20 of the main frame. The left hand end of the swinging arm 214 is connected to the depending arm of a bell crank 218 which is also pivotally mounted on the bracket 216 and is provided with an upstanding arm (not shown) coacting with mechanism of the usual construction employed in the Remington Model No. 17 machine which is mounted on the carriage unit and is operated by the line lock stop to effect operation of the portion of the line lock mechanism shown in the present instance.

From the above description of the portion of the line lock mechanism with which the present invention is concerned, it will be clear that the parts of this mechanism which are mounted on the inner removable frame are operatively connected with the parts mounted on the main frame through the separable parts 212 and 213. Thus, no manipulation of these separable parts of the

line lock mechanism is necessary in removing and replacing the inner frame assembly with relation to the main frame.

The ribbon feeding mechanism in the present machine also includes certain parts carried by the inner removable frame and parts carried by the main frame, and means have been provided for operatively connecting these parts which will permit the inner frame to be readily removed and replaced. This ribbon driving mechanism is shown in detail in application Serial No. 304,988 filed Nov. 17, 1939, and may be generally described as including a ring gear 224 (see Fig. 4) secured to the front face of the spring drum 35 to coact with a pinion gear 225 operatively connected through the usual pawl and ratchet mechanism (not shown) to a shaft 226. The front end of the shaft 226 is provided with a bevelled pinion gear 227 (see Fig. 2) cooperating with a bevelled ring gear 228. The gear 228 and the front end of the shaft 226 are both mounted on an upward extension 229 of the left-hand guide plate 86. The gear 228 is provided with an inwardly extending pin 231 which is normally disposed within the bifurcation of an arm 233 securely attached to the extending end of a ribbon feeding shaft 234. The shaft 234 is mounted for turning movement as well as longitudinal sliding movement in bearing openings in the side plates 48 and 49 of the inner frame.

Referring to Figs. 2 and 3, the shiftable ribbon feed shaft 234 is provided with a bevelled gear 236 which in the illustrated position of the shaft 234 meshes with a gear 237 at the lower end of a left-hand, vertical, ribbon spool shaft 238. A ribbon spool 239 is removably mounted in the usual manner on the upper end of the shaft 238 whereby the inking ribbon is wound thereon during rotation of the spring drum 35. The shiftable ribbon feed shaft 234 is also provided with a gear 242 which is shiftable by longitudinal movement of the shaft 234 into engagement with a gear 243 carried by the lower end of a right-hand, vertical, ribbon spool shaft 244. A ribbon spool 245 is likewise removably mounted at the upper end of the spool shaft 244 so that when the shaft 234 is moved to the right from its illustrated position, rotation of the spring drum 35 will cause the inking ribbon to be wound on this right-hand ribbon spool 245.

It will be clear from the foregoing description that the ribbon feeding mechanism of the present machine includes parts carried by the main frame and parts carried by the inner removable frame, which parts are operatively interconnected by the pin 231 and the bifurcated member 233. This connecting means obviously maintains an operative connection between the gear 228 and the shaft 234 regardless of the longitudinally shifted position of the shaft, and also permits the inner frame to be readily removed and replaced with relation to the main frame without manipulation of the parts 231 and 233.

Means are provided for enclosing the upper front portion of the present machine including the ribbon spools 239 and 245 and to provide a cover over the ends of the type bars and other parts when in normal position. This enclosing means is made readily removable in accordance with the present invention in order to permit the ribbon spools to be readily replaced and to permit the inner removable frame to be readily removed from the main frame.

Referring to Figs. 1 and 2, this enclosing means comprises a metal hood-shaped member 250 hav-

ing a substantially flat top portion with downwardly curved front and side portions. The lower side edges of the cover member 250 rest upon the upper front edges of the side portions 15 and 16 of the main frame as shown in Figs. 2 and 6. The rearward edges of the cover member 250 extend downwardly above dust shed members 262 which are permanently attached at 253 to the side plates 48 and 49 of the inner frame.

The means for removably attaching the cover member 250 in the present instance coacts between the cover member and the inner removable frame, and comprises cone-shaped pins 255 extending forwardly from brackets 257 secured to the side plates 48 and 49 of the inner frame as shown in Fig. 2. The extending ends of these pins 255 are adapted to enter tapered depressions in a reinforcing web on the inner front surface 26 of the cover member 250 as shown particularly in Fig. 1. These pins 255 thus serve to accurately locate the cover member with relation to the inner frame and yet permit the cover member to be readily removed by a forward movement thereof.

In order to normally hold the cover member 250 in position on the pins 255 and to hold the rear portion of the cover member in place, spring-pressed detent means are provided in the form of a detent arm 260 pivotally mounted at 261 on the outer surface of each of the side plates 48 and 49 of the inner frame. Each of these detent arms 260 extends substantially upward from its pivot screw 261 and a contractile spring 262 extends from a downward and rearward extension of each of the arms 260 to a pin 263 on the associated side plate. The springs 262 thus act on the arms 260 to normally hold the upper ends thereof in a rearward position wherein detent notches 264 in the arms partially embraces pins 265 extending inwardly from each side of the cover member 250.

The notches 264 at the upper ends of the detent arms 260 are substantially V-shaped as shown in Fig. 1 whereby the force of the springs 262 causes the arms 260 to so engage the pins 265 that vertical displacement of the cover member 250 is normally prevented and the cover member is pressed rearwardly with sufficient force to hold the front portion thereof securely on the projecting ends of the pins 255. The upper walls of the notches 264 in the detent arms 260 are inclined at such an angle to a vertical plane that when the rearward portion of the cover member 250 is lifted upwardly the pins 265 will cam the detent arms 260 forwardly and permit the cover member to be readily removed by this upward and forward force. In this manner the detent arms 260 serve to normally hold the cover member rigidly in place and yet permit the cover member to be readily removed when an upward and forward force is manually applied thereto.

Means are also provided in accordance with the present invention for enclosing the rear portion of the main frame, which means are adapted to be readily removed to afford access to the parts of the machine which are mounted on the rear cross member 20. Referring to Figs. 1, 4 and 6, a rear cover member is provided in the form of a pressed metal plate 270 which is adapted to fit between the extreme rearward end portions of the sides 15 and 16 of the main frame. All of the edge portions of this rear cover member 270 are bent inwardly to form flanges, and

the vertical side flange portions are adapted to fit closely inside the rearward end portions of the sides of the main frame.

Each of the side flanges of the cover 270 is provided with a hook-shaped portion 271 which is adapted to partially embrace pin 272 extending inwardly from the lower portion of each of the side members 15 and 16 of the main frame.

The hook-shaped portions 271 retain the cover member 270 against forward, rearward or upward displacement, and means are provided at the upper portion of the cover member 270 for retaining the hook-shaped portions 271 in position on the pins 272 and to normally hold the upper portion against rearward and downward displacement. This means comprises a hook-shaped detent member 274 pivotally connected at 275 to each of the side flanges of the cover 270 and having a curved portion adapted to partially embrace the upper portion of a pin 276 extending inwardly from the rear upper portion of each of the side portions 15 and 16 of the main frame.

A contractile spring 277 extends between a forward arm on each of the detent members 274 and a lug formed on the associated side flange of the cover member 270. These springs 277 act on the detent members 274 in a manner to securely hold the cover member 270 in a position wherein the front edges of the side flanges thereof engage the pins 276, and the inclined inner edge portions of the hook-shaped ends of the detent members 274 exert a camming or wedging action on the pins 276 to normally hold the cover member in an upward and inward position against accidental displacement.

When it is desired to remove the rear cover member, the upper portion thereof may be forced rearwardly so that the pins 276 cam the detent members 274 to releasing positions against the force of the springs 277 thereby permitting the rear cover to be moved outwardly and downwardly from the main frame. When it is desired to replace the cover member 270, the portions 271 are first hooked around the screws 272 and then the top portion is forced forwardly so that the inclined front portions of the detent members 274 are cammed upwardly by engagement with the pins 276 so that the noses of the members 274 pass over these pins whereupon the springs 277 become effective to securely hold the cover member in normal position.

The cover member 270 is thus effective to completely enclose the rear portion of the main frame as well as the rear portion of the carriage assembly, and yet is readily removable to permit access to any of the parts at the rear of the machine. It will further be noted that the rigid hook-shaped portions 271 at the bottom of the rear cover member pass beneath the pins 272 on the main frame, and accordingly the cover member 270 will not be inadvertently displaced or removed if the machine is raised by lifting upwardly on the lower edge of the cover member.

An improved frame structure for a typewriting machine has thus been provided wherein the main frame has top and rear cover members for protecting the internal parts of the machine against dust and dirt and to reduce the noise of operation of the machine. A particular feature of these top and rear cover members is that they may be removed easily and quickly without the use of tools to permit access to the internal parts of the machine.

This main frame of the present machine has only a few parts mounted at the rear portion and

the side portions thereof which may be easily and quickly assembled thereon. The major elements are then carried as a unit by an inner frame which permits very convenient assembly and adjustment thereof. This inner frame unit is then adapted to be readily installed or removed with relation to the main frame, which not only facilitates assembling the machine but also enables repairs to be easily and quickly made. A particular feature of this removable inner frame unit is the arrangement whereby it may be removed from the main frame merely by operating the two latch arms 110. In order to obtain this result, it has been necessary to provide separable connections between various mechanisms which are jointly carried by the inner frame and the main frame.

In the present machine, these separable connections have been included in the escapement mechanism, the back spacing mechanism, the tabulator mechanism, the margin stop releasing mechanism, the line lock mechanism and the ribbon feeding mechanism. Each of these different mechanisms is carried in part by the inner frame and in part by the main frame and the interconnecting parts have been so arranged that the inner frame may be readily removed without individually manipulating any of these connections and when the inner frame is replaced all of these connecting parts are brought into cooperative relation.

A further important feature of the present invention resides in the arrangement for adjusting the inner removable frame with relation to the main frame to afford proper operation of the machine. When the proper adjusted relation between the inner frame and the main frame is once obtained, this adjustment is not disturbed by the removal of the inner frame assembly and the same proper relation is assured when the inner frame is replaced.

The invention claimed is:

1. In a typewriting machine, the combination of a main frame including front and side portions, an inner frame, releasable latching means for securing said inner frame within said main frame, a rear cover member for closing the rear portion of said main frame, means coacting between said rear cover member and said main frame for releasably latching said rear cover member on said main frame, a top cover member for closing a portion of the top of said main frame, and means coacting between said top cover member and said inner frame for releasably latching said top cover member on said main frame.

2. In a typewriting machine, the combination of a main frame including front and side portions, a rear cover member for closing the rear portion of said main frame, means for releasably latching said rear cover member on said main frame, a top cover member for closing a portion of the top of said main frame, and means for releasably latching said top cover member on said main frame.

3. In a typewriting machine, the combination of a main frame, an inner frame removably mounted therein, locating bars adjustably mounted on said inner frame, fixed abutments on said main frame cooperating with one end of said locating bars, adjustable abutments on the main frame cooperating with the other end of said locating bars, and releasable latch means coacting between said main frame and said inner frame to normally prevent movement of

said locating bars out of cooperation with said abutments.

4. In a typewriting machine, the combination of a main frame, an inner frame removably mounted therein, guide ways in said main frame for supporting said inner frame against lateral movement, adjustable means cooperating with said inner frame for preventing endwise movement of said inner frame with relation to said main frame, and latch means for releasably holding said inner frame in cooperative relation with said guideways.

5. In a typewriting machine, the combination of a main frame, an inner frame removably mounted therein, locating means adjustably mounted on said inner frame, means on said main frame cooperating with said locating means to prevent endwise movement of said inner frame, and latch means cooperating between said main frame and said inner frame for releasably holding said locating means in cooperative relation with said means on the main frame.

6. In a typewriting machine, the combination of a main frame, an inner frame removably mounted therein, guide ways in said main frame for supporting said inner frame against lateral movement, locating bars extending substantially horizontally on said inner frame, means for adjusting the endwise position of said locating bars with relation to said inner frame, means on said main frame coacting with the rearward ends of said locating bars to prevent both up-

ward and rearward movement of the rear portion of said inner frame with relation to said main frame, means on said main frame coacting with the forward ends of said locating bars to prevent forward movement of said inner frame with relation to said main frame, and releasable holding means for preventing upward movement of the front portion of said inner frame with relation to said main frame.

7. In a typewriting machine, the combination of inner and outer frames, a locating bar extending in a fore-and-aft direction on one of said frames, means on the other of said frames coacting with the ends of said locating bar to prevent forward and rearward movement of the inner frame with relation to the outer frame, and means coacting between said inner and outer frames for releasably holding said inner frame against upward movement with relation to said outer frame.

8. In a typewriting machine, the combination of a main frame including front and side portions, a rear cover, means rigidly holding the lower portion of said rear cover against horizontal and upward movement but affording downward movement relative to the main frame, and detent means releasably holding the upper portion of said rear cover against rearward and downward movement to permit removal of the rear cover only by rearward and downward movement of the upper portion thereof.

RUSSELL G. THOMPSON
